JAMES S. LEVER, OF PHILADELPHIA, PENNSYLVANIA, ASSIGNOR
TO ROSS C. BROWNING, OF ORANGE, NEW JERSEY.

Letters Patent No. 83,980, dated November 10, 1868.

IMPROVEMENT IN BOOK-BINDING.

The Schedule referred to in these Letters Patent and making part of the same.

To all whom it may concern:

Be it known that I, JAMES S. LEVER, of the city and county of Philadelphia, in the State of Pennsylvania, have invented a certain new and improved Method of Forming Book-Covers; and I do hereby declare that the following is a full and exact description thereof

I employ pressure, rapidly and uniformly applied by India-rubber rollers, instead of the irregular and partial compression, induced by ordinary means, in compressing muslin or other surface-material on the pasteboard or other body of the book-cover. Heretofore, the paper, muslin, sheep, calf, morocco, or other material, which forms the surface of the cover, having been covered with glue or other cement, and applied on the pasteboard or other body, has been pressed down by rubbing over it by hand with a smooth-surface tool. My method operates more rapidly, and presses more uniformly. When my rollers are driven by power, my invention economizes the strength and time of the operator, and presses the surface-material on the body more uniformly, and avoids "blisters."

I will proceed to describe what I consider the best means of carrying out my invention. The accompanying drawings form a part of this specification.

Figure 1 is a cross-section of the pasteboard of a plain cover;

Figure 2 shows the same with the muslin applied, the glue being represented in red, with its thickness considerably exaggerated;

Figure 3 shows the same in the act of passing through the rolls;

Figure 4 is a cross-section of the form of the machine which I consider preferable. It is represented as adapted to be turned by a crank, but a pulley and belt will ordinarily be substituted for the crank where power is available;

Figure 5 shows the plain book-cover in a finished condition, without any exaggeration of the thickness of the paste or glue;

Figure 6 is a corresponding longitudinal section through the two parts of a book-cover, joined by the back in the ordinary manner;

Figure 7 is a corresponding longitudinal section of the sheet-metal plate, adapted to receive and support the cover while being thus treated; and

Figure 8 shows the cover in position on the plate.

Similar letters of reference indicate corresponding parts in all the figures.

A A are the bodies of two India-rubber rollers. They are mounted on iron shafts a, supported in a housing, B, and pressed down with adjustable force, by means of screws, as indicated by C. There may be adjusting-springs, as indicated by D, to allow the upper roller to rise a little in receiving each book-cover, and this property will add somewhat to the perfection of the operation of the machine in making bevel-edged covers, and other forms of book-covers not plain.

M is the pasteboard, for which may be substituted wood or other material, which is employed for the body of the cover, and m is the muslin, for which may be substituted paper, leather, or other material, to make the ornamental or durable surface. The glue, paste, or other cementing-material, is indicated in red in some of the figures, as above suggested.

A little glue is always liable to exude beyond the turned-over edges of the surfacing-material m. To avoid getting this glue on the lower roller, and thus transferring it to the upper roller, and defacing the surface of the succeeding covers, I mount each cover on a plate of sheet-metal, N, which may be common tinned iron. To keep the covers exactly in place on such metal, I glue, or otherwise affix across the middle of the plate, a piece of pasteboard, n, which corresponds to the thickness of the material M. By placing the freshly-prepared cover on the plate of sheet-metal, in such position that the parts match properly together, that is to say, taking care to have the piece n of a width a little less than the width of the thin part which forms the back of the book, I introduce the plate N n, with its load, M m, and pass the whole rapidly between the rollers A A. The glue which exudes remains on the upper surface of the plate N, and the operation may be repeated for any number of times, without smearing either of the rollers.

Having now fully described my invention,

I claim the within-described means or method for cementing the muslin or other surface-material upon the boards of book-covers.

JAS. S. LEVER.
